REFRIGERATOR DOOR CONSTRUCTION

Robert A. Jansen, Cincinnati, Ohio, assignor to Avco Manufacturing Corporation, Cincinnati, Ohio, a corporation of Delaware

Application December 15, 1954, Serial No. 475,452

5 Claims. (Cl. 20—35)

The present invention relates to a refrigerator and, more particularly, to an improved door for a refrigerator.

The invention relates more specifically to a door having an outer shell and an inner liner both formed from sheet metal. As will be described completely in this specification, the liner and shell when assembled have great strength and are free from twisting and significant deflection under load.

A breaker strip of low thermal conductivity is provided between the shell of the door and the liner to minimize heat transfer therebetween. The breaker strip is not relied upon for strength purposes and, through the unique construction disclosed in this specification, is attached to both shell and liner in such a way as to accommodate sizable differences in thermal expansion as well as dimensional variations incidental to mass production. Despite the relative movement possible between the breaker strip and the associated door components, the breaker strip is firmly mounted and clamps a resilient gasket securely in position adjacent the edges of the door.

Due to the overall construction of the refrigerator door set forth, it is possible to straighten twisted door components, such as the outer shell, after the basic components of the door have been assembled. In this way, fabrication of a strong, flat door which will seal properly with the refrigerator cabinet is assured.

In view of the foregoing, it will be understood that a broad object of the present invention is the provision of an improved refrigerator door.

Another object of the invention is the provision of a door that can be fabricated by mass production methods and is not critical with respect to minor dimensional variations.

A more specific object of the invention is to provide an improved door construction incorporating relatively rigid inner and outer components which may be selectively fastened together to fabricate a flat, strong, durable door.

A still further object of the invention is the provision of improved mounting means for securing a breaker strip to a refrigerator door whereby the breaker strip and door components may move relative to each other to accommodate differential thermal expansions.

Another advantage of the invention is the design of improved spring clips used for holding the breaker strip in place. These clips are designed to be removably attached to the breaker strip so that the breaker strip may be handled without loss of clips during assembly.

A feature of the invention is the design of the breaker strip whereby an associated gasket is clamped snugly to the refrigerator door and is held substantially parallel to the edges of the door.

The novel features that I consider characteristic of my invention are set forth in the appended claims; the invention itself, however, both as to its organization and method of operation, together with additional objects and advantages thereof, will best be understood from the following description of a specific embodiment when read in conjunction with the accompanying drawings, in which:

2

Figure 1 shows to a reduced scale a perspective view of a refrigerator having a door of the improved type including the teaching of this invention;

Figure 2 is a cross sectional view taken on plane 2—2 of Figure 6 showing the breaker strip in cross section and the spring clips for securing it to the door;

Figure 3 is a cross sectional view taken on plane 3—3 of Figure 6 showing one corner of the inner door liner adjustably secured to the outer shell of the door;

Figure 4 is a longitudinal sectional view taken on plane 4—4 of Figure 2 showing one of the spring clips for securing the outer edge of the breaker strip to the door;

Figure 5 is a view taken on plane 5—5 of Figure 2 showing the type of spring clip used for securing the inner edge of the breaker strip to the door; and

Figure 6 is an elevational view of the assembled door.

Referring first to Figure 1, there is shown a refrigerator cabinet, generally designated 1, to which an access door 2 is hingedly secured, as at 3. The refrigerator cabinet 20 includes a freezer section 4 and an upper evaporator 5 which extract heat from the cabinet so that comestibles may be stored under refrigerated conditions.

The access door comprises an outer shell, generally designated 6, and an inner liner 7. Secured to the inner liner may be a plurality of shelves 8 as well as a storage compartment 9 for butter and similar foods. A water tank 10 may be provided at the top of the door.

Extending between outer shell 6 and liner 7 is a thermal breaker strip 11 which may be made from high impact polystyrene. Other materials of relatively low thermal conductivity may be used, as is well-known to those versed in the art. In addition to improving the appearance of the door and giving it a finished look, the breaker strip impedes heat transfer between the shell and liner.

35 A resilient gasket 12 surrounds the edge of the door and bears in sealing relationship against the refrigerator cabinet when the door is closed. As will be discussed fully later in this specification, breaker strip 11 also clamps the gasket evenly and securely in sealing relationship against door shell 6.

Attention is now directed to Figure 6 which shows additional structural details. As illustrated in this figure, the four corners of the outer shell 6 are reinforced by integrally welded gussets 13. Such gussets are shown at the upper and lower corners of the door where the breaker strip has been broken away to reveal the construction more clearly.

The inner liner 7 of the door defines a relatively deep recess to accommodate the food shelves 8. The deep drawn formation of the recess gives the liner, which may be made from sheet metal, considerable strength. The strength of the liner is further increased by the provision of flanges 14 which surround the liner and which join at enlarged corners 15 which overlie the gussets 13 of the outer shell. A bolt 16 at each corner of the liner secures it to an associated gusset.

60 The attachment of the liner and shell can be better understood by reference at this time to Figure 3. This figure shows gusset 13 to which a threaded nut 17 is rigidly attached, as at 18. Corner 15 of the liner is spaced slightly from the gusset by a plastic washer 19. Bolt 16 clamps the corner of the liner, washer, and gusset securely together.

65 A couple of washers are shown at 20. The washer immediately adjacent the liner may also be made of plastic, the plastic washer 19 as well as this plastic washer combining to reduce heat transfer between the liner and the gusset. Attention is called at this time to slot 21. A similar slot is provided in each of the lower corners 70 of the liner for a purpose to be described more fully later in this specification. Slots need not be provided in the

upper corners of the liner but rather relatively snug holes should be provided for upper bolts 16.

Returning to a consideration of Figure 6, it will be noted that elongated slots 22 and 23 are formed in in-turned flange 24 of the outer shell, and flange 14 of the inner liner. These slots extend parallel to the adjacent edges of the members in which they are formed and receive spring clips which hold the breaker strip 11 to the door, as will now be explained.

The breaker strip mounting is best shown in Figure 2. Flanges 14 and 24 of the liner and shell, respectively, are shown in cross section, the section being taken directly across slots 22 and 23. A spring clip, generally designated 25, is positioned in slot 22. Another spring clip of different design, designated 26, is received by slot 23.

The spring clip 25 comprises bifurcated resilient legs 27 which are inturned at 28 to produce a camming action to draw the clip against flange 24 when the clip is forced into slot 22.

Legs 27 are formed integrally with a U-shaped breaker strip retainer 29 which receives the outer edge 30 of the breaker strip. Retainer portion 29 of the clip is received in a slot 31 formed in the edge of the breaker strip (see Figures 2 and 4). The clip may further be confined in its movements relative to the breaker strip by groove 32 and pocket 33 formed on the underside of the breaker strip. A small spring detent 34 is formed on the spring clip and is received by pocket 33. In this manner the spring clip is kept in engagement with the breaker strip during the assembly operation.

The cross section of the gasket is also illustrated in Figure 2. Attention is called to the presence of an integral rib 35 formed on the gasket and engaged behind a longitudinal ridge 36 formed at the outer edge of the breaker strip. The ridge 36 engages behind the rib 35 and the ridge is pulled against web 37 of the gasket by the resilient force of spring clip 25 when it is fully engaged with slot 22, as shown in Figure 2.

Attention is now directed to the formation of spring clip 26 which is essentially U-shaped, one leg of the U being received in a slotted plastic projection 38 formed adjacent the inner edge of the breaker strip. The projection 38 passes through slot 23 and supports the spring clip 26 in resilient engagement with flange 14.

The spring clip includes a wide head portion 39 with prongs 40 in engagement with the slots 41 of projection 38. See Figures 2 and 5. In this way, the spring clip is prevented from coming off of the breaker strip.

The other leg of the spring clip is bent slightly at 42 defining an inclined portion 43 which bears against one edge of slot 23, tending to draw the breaker strip against the face of flange 14. A planar area 44 is formed on the breaker strip to assure that no portion of slot 23 will be visible.

With particular reference to Figures 4 and 5, it will be noted that spring clip 25 and projection 38 have relatively great longitudinal clearance in their respective slots. Thus, the breaker strip and its associated spring clips may execute relatively large movements incidental to temperature change without setting up any severe stresses in the breaker strip. The clearance of these members in their slots is such that relative movement is accommodated in a direction parallel to the larger dimensions of the breaker strip.

To illustrate, attention is again invited to Figure 6 showing the disposition of a plurality of slots 22 and 23 in the shell and inner liner of the door. It will be understood by those skilled in the art that a series of spring clips 25 and 26 are engaged with these respective slots, removably securing the breaker strip to the door components and holding the door gasket snugly against flange 24. As also illustrated in this figure, the slots extend parallel to the major linear dimensions of the breaker strip. It is parallel to these dimensions that the major

differential movements incidental to temperature change may be expected.

No spring clips are provided immediately adjacent the corners of the shell or liner since at these points the differential movements to which the breaker strip may be subjected may combine to shift slightly the corner of the breaker strip and restraint at this point may set up severe stresses.

Not only is the present design excellently adapted to compensate for thermal changes, it is excellently suited for mass production methods in which dimensional variations are always present. As illustrated in Figure 2, clearance is provided at 44a between the edge of the breaker strip and the spring clip 25 to permit relative changes of position incidental to manufacturing variations. Thus, considerable change of transverse position of the breaker strip may be accommodated without sacrifice of strength or secureness of attachment of the breaker strip and gasket to the door.

To fully appreciate the nature of this invention, it must be understood that the strength of the door assembly results from the box structure of the combined shell and liner. The breaker strip in no way contributes to the strength of the door. In prior art constructions in which the door liner and breaker strip are made unitary, relative movement between the breaker strip and the door shell cannot normally be tolerated since the breaker strip is relied upon for strength purposes. The only way of avoiding this is by internal bracing of the door which is relatively expensive and complicated. By virtue of the present invention, however, the liner and breaker strip being separately formed, the liner may be relied upon for strength purposes and the breaker strip may move relative to both the door shell and liner, thereby completely avoiding any serious stresses in the breaker strip.

During assembly the door shell and liner are first bolted together at the four corners. The two upper corners are securely bolted whereas the lower corners are only lightly secured together. The breaker strip, with spring clips

40 and gasket in position, is then forced against the shell and liner, the various spring clips engaging their receiving slots and drawing the breaker strip securely against the door. Simultaneously, the gasket is clamped to the door and is positioned by the ridge 36 of the breaker strip.

45 The door is then checked for flatness. Should it be found that it has a slight twist, a torque is applied to the lower portion of the door to restore it to a planar condition. The lower bolts, not being fully tightened, will permit this operation and will hold the door when moved to a planar position. Thereafter, the lower bolts are securely tightened and the door will retain indefinitely a perfectly true, flat form ideally suited for sealing with the refrigerator cabinet.

50 Since the lower corner bolts are tightened after the assembly of the door, plastic caps 45 are provided in the breaker strip opposite the lower corner bolts. These caps can be snapped into the breaker strip as the final assembly operation.

During straightening of the door, slight relative movement will occur between the lower corners of the liner and the lower gussets of the door. Slots 21 (see Fig. 3) permit this movement and are desirably aligned with the diagonal dimensions of the door.

55 During the straightening operation, movement may also occur between the breaker strip and the shell and liner. The longitudinal clearance of slots 22 and 23, as well as the edge clearance at 44a, will accommodate such movement. The importance of such freedom of movement will be understood when it is remembered that the breaker strip is assembled with the door prior to the straightening operation.

It will be noted that an advantage of this design is that no holes are necessary through the web of the gasket. In this way, alignment problems of fasteners passing through the gasket are avoided.

The various features and advantages of the design and construction disclosed are thought to be clear from the foregoing description. Various other features and advantages not specifically enumerated will undoubtedly occur to those versed in the art, as likewise will many variations and modifications of the preferred embodiment of the invention illustrated, all of which may be achieved without departing from the spirit and scope of the invention.

Having described a preferred embodiment of my invention, I claim:

1. In a refrigerator door, an outer sheet metal shell including a flange extending inwardly from each edge thereof, an inner liner nested within said shell and including a flange extending outwardly from each edge thereof towards said first mentioned flanges, said flanges of said liner being joined at the corners thereof, gussets rigidly secured to the corners of said shell, said corners of said liner overlying said gussets and being secured thereto, said flanges defining a plurality of elongated slots extending parallel to the length of said flanges, a breaker strip extending between said flanges of said shell and liner, projections formed on said breaker strip for engaging the slots of said flanges on said liner, a plurality of spring clips releasably secured to the outer edge of said breaker strip in position to resiliently engage the slots in said flanges of said shell, a plurality of spring clips engaged with said projections of said breaker strip in position to resiliently engage the slots in said flanges of said liner, the longitudinal extent of said spring clips and said projections being less than the length of said slots in said flanges whereby relative movement between said breaker strip and said flanges is permitted incidental to differential thermal expansion.

2. Apparatus as defined in claim 1 and, in addition, a resilient gasket surrounding the outer edge of said breaker strip and clamped thereby against said flanges of said shell.

3. In combination in a refrigerator door, an outer shell including a flange extending inwardly from each edge thereof, an inner liner including a flange extending outwardly from each edge thereof towards said first mentioned

flanges and spaced laterally therefrom, the corners of said liner being secured to said shell, said flanges defining a plurality of elongated slots extending parallel to the length of said flanges, a breaker strip extending between said flanges of said shell and liner, and a plurality of spring clips attached to said breaker strip and resiliently engaged with the sides of said slots whereby said breaker strip is firmly secured to said shell and liner, said clips being smaller in longitudinal extent than the slots whereby said breaker strip may sustain differential thermal expansion relative to said shell and liner without damage.

4. In combination in a refrigerator door, an outer shell, an inner liner, said shell and liner being formed of sheet metal and being adjustably connected at the corners thereof to permit straightening of the door after assembly, said liner being nested within said shell and defining an air space therebetween, a plurality of elongated slots in said liner and shell, a plurality of spring clips movably and releasably engaged in the slots, a breaker strip spanning the air space and movably engaged with certain of said spring clips whereby movement of said breaker strip relative to said shell and liner incidental to thermal expansion and straightening is possible.

5. In combination in a refrigerator door, an outer shell, an inner liner, said shell and liner being formed of sheet metal and being connected together at the corners thereof, said liner being nested within said shell with the adjacent edges defining an air space therebetween, a plurality of elongated slots adjacent the edges of said liner and shell, said slots being formed parallel to the edges, a breaker strip spanning the air space, spring clips fixedly engaged with said breaker strip and movably and releasably engaged with the slots of said liner, and spring clips adjustably engaged with said breaker strip and movably and releasably engaged with the slots of said shell.
